RECORD PUNCHING MACHINE

Charles R. Doty, Yonkers, N. Y., assignor to International Business Machines Corporation, New York, N. Y., a corporation of New York

Application April 12, 1944, Serial No. 530,662

22 Claims. (Cl. 164—115)

This invention relates to record controlled tape punching systems and more particularly to the type of punching system in which data on a record card punched according to one code is converted to another code and punched on a tape.

The main object of the invention is to interpolate data on the tape as the latter is being punched under control of the sensed record card so that when the punched tape is utilized to control a tape controlled printing machine the interpolated designations punched at predetermined positions of the tape will cause the printing of corresponding designations or spacing of the tape to render the meaning of the printed tape more intelligible.

As an explanation for the above, it is well known that the punching of a tape in the Baudot code may be derived from data punched on a record card according to another different or statistical code. Such record cards may have previously been utilized to control record controlled accounting machines, sorting machines and the like and accordingly such cards are made up with a plurality of card columns, one or more making up a card field. Such card fields are usually adjacent and when utilized in a tabulating system they do not usually include or require the representations of the extra characters, or spaces to render the data intelligible. One example would be two card fields punched to represent 12853810987, all run together which is intended to mean \$128,538,109.87 and the latter indicates the manner in which the data should be printed under control of the punched tape so that it can be understood by the reader. In the present machine the necessary significant characters, punctuation, spaces, etc. are interpolated as tape punching occurs.

A feature of the invention is the provision of means responsive to sensing of predetermined positions of the record card to cause, by interpolation, an extra punching operation of the tape to punch representations of the desired characters, space, etc., necessary at such column positions.

Another feature of the invention is to provide storage of such extra character representations, space, etc., in a master or pattern card, the card column positions of which are concurrently sensed with the record card.

Another feature of the invention is to provide for the sensing of the perforation of the master or pattern card at predetermined column positions and upon determination that a perforation

exists to interpolate punched data by causing the initiation of the operation of the tape punching machine to punch in the Baudot code such extra character representations, as space, etc.

5 Another feature of the invention provides for suppression of tape punching under control of a card column of a record card when a perforation is concurrently sensed on the master or pattern card until the extra punching cycle of the tape punching machine is performed to punch the extra designation called for by the pattern card.

10 Another feature of the invention provides for the suppression of column spacing of the pattern and record cards which would normally follow each tape punching cycle of the tape punching machine but enable the normal tape spacing function of the tape punching machine for spacing the extra designations punched on the tape.

15 Another feature of the invention provides for the suppression of column spacing of the pattern and record cards which would normally follow each tape punching cycle of the tape punching machine but enable the normal tape spacing function of the tape punching machine for spacing the extra designations punched on the tape.

20 Another feature of the invention relates to the provision of means for punching the tape at a succeeding column position under control of the sensed data on the record which punching operation was suspended during the interpolated

25 tape punching operation. Concurrent with this operation, additional means comes into operation to prevent the master or pattern card from being effective to repeat its control during the cycle of operation that the tape punching machine is operated to punch said sensed data on the record.

30 Another feature of the invention relates to a plurality of control means which select for operation the desired tape punch control magnets of the tape punching machine to punch the extra coded designations and the provision of means to selectively associate such control means with the master or pattern card sensing means. This selective arrangement enables interpolation of desired data at predetermined positions of the tape.

35 Other objects of the invention will be pointed out in the following description and claims and illustrated in the accompanying drawings, which disclose, by way of example, the principle of the invention and the best mode, which has been contemplated, of applying that principle.

In the drawings:

40 Fig. 1 is a plan view of the apparatus showing diagrammatically the electrically connected record sensing and tape perforating units.

45 Fig. 2 is a fragmentary portion of a statistical card shown perforated to represent four numeral data groups in adjacent card fields.

50 Fig. 3 is a fragmentary portion of a pattern or

master card shown as a matter of illustration perforated to initiate extra punching cycles of the tape perforating unit at predetermined card column positions of the master or pattern card carriage to intersperse coded designations on the tape.

Fig. 4 is a tape section showing the coded designations for characters represented on the tape which are perforated by the tape perforating unit.

Fig. 5 is a fragmentary portion of a tape which would be perforated under control of the statistical card indicating the manner in which extra coded designations are interspersed on the tape to demarcate numeral groups and the manner of interspersing other coded designations at other card column positions of the tape for demarcating the thousands denominational orders of a numerical group and the decimal orders of another numerical group.

Fig. 6 is a timing diagram of the cam controlled contacts utilized in connection with the electrical wiring.

Fig. 7 is a sectional view of a well known form of statistical card sensing unit showing principally the instrumentalities utilized in connection with the present improvement.

Fig. 8 is a detail of the escapement mechanism of the record sensing unit.

Fig. 9 is a view in side elevation of the tape perforating unit.

Fig. 10 is a sectional view of the analyzing means for the pattern or master card, forming part of the record sensing unit.

Fig. 11 is a diagram of circuit connections of the parts of the apparatus comprising the present improvement.

Before describing in detail the construction and operation of the present improvements, it should be observed that for the purpose of illustration the present improvement is shown in connection with a record controlled tape perforating apparatus of the form shown and described in full detail in the patent to C. R. Doty, No. 2,340,800, granted February 1, 1944. The individual record sensing and tape perforating units shown in detail in this patent are diagrammatically shown in Fig. 1 wherein it will be seen that they are interconnected by a cable connection CC. To understand the operation of such apparatus a general outline of the functional operations thereof will be set forth briefly.

Individual record cards C (Fig. 2) having columns of either alphabetical or numerical data or both recorded thereon in the Hollerith code are presented to a sensing station by means of a reciprocable card carriage comprising a pusher 13 (Fig. 7). The record card C is fed column by column to the group of individual sensing brushes 12, one sensing brush 12 being provided for each index point position. The sensing brushes 12 (Fig. 11) are electrically connected to individual translating relays of the group RR, RX, RO, R1-R9, which relays are energized selectively in accordance with the sensed data designations on the record cards. A plurality of control relays R10, R11, R12, R13, R14 are connected to certain ones of the translating relays so as to be energized selectively in accordance with the data sensed on the cards.

The aforementioned patent discloses in complete detail the translating mechanism controlled by the translating relays which, through their associated contacts, are effective to translate designations sensed in the statistical code to the

5-unit telegraphic or Baudot code and accordingly control selectively the energization of the tape punch control magnets 290 in different code combinations, thereby causing the code designating perforations representing the data sensed on the record cards to be punched in the tape 200.

The card sensing mechanism will only be described in sufficient detail for a full comprehension of the present invention, since details of the sensing unit are disclosed in the patent to Doty, No. 2,340,800. Furthermore, in view of the fact that the mechanical arrangement of the card feeding and ejecting mechanism is substantially the same as that embodied in the machine known as the "International Duplicating Key Punch" and "Alphabetical Verifier," such as shown, for example, in U. S. Patent No. 1,914,263, dated June 13, 1933, and U. S. Patent No. 2,107,161, dated February 1, 1938, a condensed description is deemed to be sufficient.

Referring to Fig. 1, the record cards C to be sensed or analyzed are placed in the magazine 10 from which they are advanced singly by a picker 11 toward the left, to present the first column of perforations to a card sensing position above the sensing brushes designated 12 in Fig. 7. In this position the reciprocable card carriage comprising a pusher 13 and a guide 14 engages the card and advances it column by column under control of the escapement mechanism to be described later.

The operation of the card feeding mechanism for feeding a card from the magazine 10 and placing it upon the card carriage to the initial sensing position is fully explained in Patent No. 1,772,186, granted to F. L. Lee et al. for Duplicating punching machine.

The escapement mechanism of the record sensing unit is of the same general nature as that disclosed in the Schaaff Patent No. 1,426,223 modified for electrical control as in the Doty Patent No. 2,340,800 and a brief description thereof will now be given.

When the card is in a position above the sensing brushes 12, the column by column advance of the card carriage is controlled by an escapement mechanism which, in turn, is responsive to the energization of the escape magnet 40 (Fig. 7). Upon energization of magnet 40 its armature 41 will be rocked about a pivot in a clockwise direction and through a screw 42 secured to an arm secured to rod 43 will rock the rod 43 counterclockwise against the tension of a spring 44. The rod 43 is rocked as an incident to each spacing operation and has secured to one end thereof oppositely extending arms 45, 46 (see also Fig. 8) of which arm 46 is provided with a laterally extending pin for engagement with an enlarged opening in a stepping dog 47 which is loosely pivoted on rod 43. Opposite arm 45 is provided a pin extending into a slot formed in the locking dog 48. When rod 43 is rocked, arm 46 will, through its pin and slot connection with dog 47, lift the latter out of one of the notches of the escapement rack 15 movable with the card carriage and at the same time arm 45 will depress locking dog 48 into a notch between the ratchet teeth. At this time, spring 49 advances the loosely pivoted dog 47 a short distance just sufficient to permit this dog to move over the top of the next tooth. When the locking dog 48 is again raised, stepping dog 47, due to the movement of the rack 15 and the card carriage, will ride down along the next tooth until it strikes the bottom thereof and the spring driven card carriage is thereby ar-

rested. It is sufficient to know thereof that for each energization of the escape magnet 40 the escapement rack 15, and therefore the card carriage, is moved the distance of one card column through the action of the pusher 13 and the forward guide 14 on the statistical card. Also in Fig. 8 are shown the "floating cam" contacts 149 which are well known in the type of machine now being described. One blade of contacts 149 is shifted by an arm 150 which is loosely pivoted on the rod 43 and which has a depending extension resting upon the upper edge of the stepping dog 47 so that during escapement from one column to another the incidental raising of the stepping dog 47 and the elevation of arm 150 will cause the opening of the contacts 149 during the period that the dog 47 is raised. When the card carriage has come to rest after having escaped through the distance of a card column, contacts 149 will come to normal position in which they are closed.

Incorporated in the record sensing unit shown in Fig. 1 is an additional sensing device adapted to sense the perforations on the master card M as it will be called hereinafter (Fig. 3). The record sensing unit shown in the aforementioned Doty Patent No. 2,340,800 is intended to have such supplemental master card sensing device and since the details thereof are not disclosed in this patent, a description will be given of this arrangement.

The master card sensing device is shown in Fig. 10 and is well known as part of the International Duplicating Key Punch. This master card sensing device is fully shown and described in the U. S. patent to Lee and Daly, No. 1,976,618, granted October 9, 1934 to which reference may be had for further details of construction.

For a general understanding thereof it will be observed that the escapement rack 15 is provided with extensions or arms 37 and 47 (Fig. 10), between which the master card M is positioned in columnar alignment with the statistical card C. This comprises, therefore, a card carriage for the master card which is adapted to be moved back and forth with the escapement rack 15. Positioned about the master card M is a contact roller 50 which is insulated from the frame of the machine and supported by a door 51 pivoted at 52. Directly below the roller 50 are brushes 53 carried by a bar 54 which is normally in the position shown in Fig. 10, holding the brushes down out of engagement with the master card M. The magnet 55, upon energization, will attract its armature 56, actuating linkage 57 to cause movement of the brushes 53 into engagement with the master card M.

It is well known that a series of brushes 53 is provided to analyze all the index point positions of the master card M but in Fig. 11 only the sensing brushes 53 for analyzing the 7, 8 and 9 index point positions of the master card are shown because only such positions are utilized herein to effect extra coded punchings in the tape sensing unit. It should be observed that prior to the beginning of the concurrent analysis of a master card M and a statistical card C the magnet 55 is energized to elevate the sensing brushes 53 and by circuit connections described in the Doty patent the magnet 92 (Fig. 7) is also energized to elevate the brushes 12 for sensing the statistical card C. Thereafter, there is a concurrent step-by-step escapement of the master card M and statistical card C and whenever the brushes 53 encounter perforations at the index point posi-

tions in which they are aligned, circuits will be closed through such perforations to effect certain functions in the tape sensing unit, as will be described hereinafter.

5 The tape perforating unit

Fig. 9 represents the construction of the tape perforating unit to disclose the elements necessary to understand the present improvement.

10 To secure full details of the construction and operation of this unit, recourse may be had to the aforementioned patent to C. R. Doty, No. 2,340,-800. In general, the perforating portion includes individual punch elements 210, one for each unit of the Baudot code, which punch elements are reciprocable in a die block 211 to perforate the tape 200 according to the punch elements selected for operation. 217 represents interposers individual to punch element 210, each of which has a strap 218 which is operated by an eccentric cam 219 carried by the drive shaft 220 of the tape perforating unit. Normally, during the rotation of the eccentric cam 219 each interposer is moved downwardly and upwardly by the supporting eccentric about the pivotal connection 216 formed by the end of the interposer engaging the recess of the related punch element.

30 For each interposer 217 there is provided an individual latch arm 222. Whenever it is desired to select a punch element 210 for operation the related latch arm 22 is rocked in a clockwise direction so that its latch fingers 224 engage and latch the free end of the related interposer 217. Thus, upon latching of an interposer 217 and 35 rotation of the eccentric 219 the said interposer is positioned by the eccentric about the pivotal connection formed by the latch arm 222 and the latched end of the interposer to force the related punch element 210 downwardly, thereby causing the tape 200 interposed between the lower ends of the punch elements 210 and the die block 211 to be perforated.

40 The control means for selectively positioning the latch arms 222 and thereby select the punch elements 210 for operation consists of the punch selecting magnets 290. The armature 291 of each magnet 290 has connected thereto an arm 292 and the latter has a call wire connection 293 between the related arm 292 and the latch arm 222. 45 Hence, the energization of each magnet 290 positions the related latch arm 222 so as to effect the operation of the related punch element 210.

50 Other elements shown in Fig. 9 are involved in the punching operation but they are not described herein since full details of their construction and operation may be had by reference to the aforementioned patent to Doty, No. 2,340,800.

55 By means more fully described in the aforementioned patent, substantially centrally located feed perforations 202 (Fig. 4) are formed as the tape is perforated. The paper tape 200 is drawn from a supply roll (not shown) to the punching station by a feed roll 240 secured to a drive shaft 241. Said feed roll 240 is formed at its periphery with 60 teeth 243 which cooperate with the feed perforations 202 of the tape 200. The step-by-step rotation of the feed roller 240 feeds the tape 200 so as to present successive columns of the unperforated tape 200 to the punch elements 210.

65 70 The operation of the punching mechanism of the tape perforating unit, as well as the operation of the tape feeding mechanism performed in the necessary sequence, is effected upon energization of the tape clutch control magnet 280, shown only 75 in the wiring diagram of Fig. 11. In the Doty

patent, complete details are shown of the manner in which such magnet initiates the operation of the tape perforating unit. For understanding the present improvement it is sufficient to know that this initiates the operation of the drive shaft 220, the shaft 241 for feeding the tape and other operating elements of the tape perforating unit to effect the tape punching and feeding operations.

Operation

The general operation of the machine will now be given in connection with the circuit diagram of Fig. 11 and a more detailed description will be given of the present improvements exemplified by the example of Fig. 5 when that point of the specification is reached.

It will be assumed that the card carriage of the record sensing unit has been returned to its normal position, that is, to card column 1 position, at which time latch contacts 35 and floating cam contacts 149 (Fig. 11) are both closed. It will also be assumed that a tape is to be perforated in the 5-unit Baudot code to represent in such code the four numbers represented on the record card C by coded perforations according to the Hollerith statistical code.

At column 1 position of the card carriage a circuit will be closed from the line 300, through said contacts 35 and 149, contact roll 91, brush 12, sensing the 1 perforation of column 1 coils of the translating relay R1 and control relays R13 and R14 to line 301, energizing said relays.

At the same time a circuit is completed from contacts 149 through the tape punch clutch magnet 280 and cam controlled contacts C1 to line 301, energizing the clutch magnet. This initiates a cyclic operation of the tape perforator. In view of the fact that letter or numeral representing perforations in the control tape must be preceded by a respective code signal or designation, such as "letters" or "figures," the tape is not perforated during this cyclic operation of the machine to represent the digit 1 but is first perforated at code positions 1, 2, 4 and 5 to represent "Figure Shift" (see Fig. 5). The circuit arrangement whereby the corresponding punch selecting magnets 290 are energized to effect code designations on the tape is completely described in the Doty Patent No. 2,340,800 and since it is not involved in the present invention, further description is unnecessary. In this perforating operation it should be noted that R16 relay is energized to open the R16a contacts, thereby preventing an impulse from being directed to the escape magnet 40 when cam contact C2 close after the card sensing operation. In the present arrangement the circuit for said magnet 40 is from line 300, through latch contacts 35, through relay contacts R15a, relay contacts R16a, through cam contacts C2, escapement control magnet 40, through normally closed D1 contacts comprising part of the new circuit arrangement, to line 301. Since an impulse is not directed to said magnet 40, the card carriage will not be spaced and it will remain in the column 1 sensing position and the aforementioned selected translating and control relays will remain energized. The cyclic operation of the tape perforating unit is reinitiated when cam contacts C1 close at the end of the first tape perforating cycle. During the second cycle of the tape perforator punch by translating circuits described in the Doty patent, said translating and control relays select the tape punch magnets 290 for perforating the tape at the 1, 2, 75

3, and 5 code positions to represent the numeral 1 (see Fig. 5). After this tape perforating operation, cam contacts C2 close, thereby directing an impulse by the circuit previously outlined to the escape magnet 40 which spaces the record card to card column 2. Of course, the tape is advanced one step after this tape perforating operation.

Upon energization of the escape magnet 40, an operation of the above described escapement 10 mechanism of the sensing unit is effected and floating cam contacts 149 are opened until the next column is presented to the sensing brushes. Opening of contacts 149 causes the deenergization of the translating and control relays previously energized. Upon the closure of the floating cam contacts 149 when the card carriage comes to rest at card column position 2, the translating and control relays will be selectively energized under control of the perforation at the 2 index point position in the record card C. Through the translating relay system shown in detail in the Doty patent, certain tape punch magnets 290 will again be energized to perforate the tape to represent 2 in the Baudot code. Following this tape perforating operation, the card carriage of the sensing unit is spaced a card column and the tape likewise. This will present the third column of the card to the sensing brushes and the 8 digit representing perforation thereon 15 is sensed and through the translating system the corresponding digit is represented on the tape in the Baudot code. It is thought unnecessary to repeat such operations of the machine since they are merely repetitions of the aforescribed operations.

After the third column of the record card C has controlled the tape perforating operation, the card carriage is spaced to card column position 4, at which time there is a concurrent 20 analysis of the 5 digit representation in card column 4 of the record card C and the perforation at the 7 index point position of the master card M. The tape perforating operation under control of the record card is now suppressed and instead perforations are made in code positions 3 and 4 of the next column of the tape (see Fig. 5) to represent a comma. This comma in the decimal notation system demarcates the thousands orders of a number from the lower ordered digits. With such coded designations in the perforated tape the latter, when utilized to control a tape controlled printing machine, will cause the comma to be inserted between the hundreds and thousands denominational digits, 25 enabling such number to be properly read.

When the card carriage comes to rest in the 4 card column position of both the master card and record card C, a circuit is closed from the line 300 through latch contacts 35, floating cam contacts 149, to contact roll 50, through the contact brush 53 of the master card sensing means 30 analyzing the perforation at the 7 index point position of the fourth card column, the C relay, thence through E1 contacts now closed, through D relay to line 301, energizing both the C and D relays.

The C relay remains energized until the E relay opens E1 contacts, effected when cam contacts C2 close, completing a circuit from line 300, through latch contacts 35, relay contacts R15a, R16a, cam contacts C2, D2 relay contacts now closed, E relay coil to line 301. A stick circuit for the E relay is provided by E2 relay contacts, FC contacts, and latch contacts 35 back to line 300. Therefore, the E relay is re-

tained energized until the FC contacts open when the card carriage spaces from column 4 to column 5. E relay opens the E1 contacts to break the energizing circuit for the C relay and the purpose of this circuit arrangement is to retain the C relay energized long enough to control a tape perforating operation and deenergize the C relay after it has been employed once to control a tape perforating operation and thus prevent a repetition of its use in a following tape perforating cycle, during which cycle the tape is perforated to represent the sensed digit representing perforation on the record card C.

D relay will close its stick contacts D3 and the stick circuit will extend back through such relay contacts, cam contacts C6, latch contacts 35 to line 300 and cam contacts C6 will hold the D relay energized for a greater part of the tape punch cycle in which the extra coded designation is punched on the tape. D relay will open its D1 contacts to open the impulse circuit of the escapement control magnet 40 so that during the cycle in which the extra coded designations punched on the tape, the circuit to the escapement control magnet cannot be completed and the card carriage will remain at card column position 4. At such card column position the perforation at the 5 index point position of the record card will remain to be sensed and certain of the translating and control relays will be energized. Through the translating system of the Doty Patent No. 2,340,800, an attempt will be made to select certain of the tape punch magnets 290. However, prior to the operation of the translating system the D relay magnet has transferred its D4, D5, D6, D7 and D8 contacts, thereby opening the circuits between the tape punch magnets 290 and the impulse selecting circuits 306-310 of the translating system of the Doty Patent No. 2,340,800. Energization of relay D through its 4, 5, 6, 7 and 8 relay contacts prevents the selection of the tape punch magnets 290, thereby suppressing the perforation of the tape in accordance with the 5 perforation of column 4 of the record card C. Since it is assumed that the C magnet has been selected for energization the latter will close the C1 and C2 contacts to select the tape punch magnets 290 to perforate the tape at code positions 3 and 4. This is the coded representation for the comma as appears in Fig. 4. The energizing circuit is from the line 300, through cam contacts C5, through C1 relay contacts now closed, through D6 contacts to the 3 tape punch magnet 290, to line 301. A similar circuit can be traced for selecting by the C2 contacts 4 tape punch magnet 290. This perforates the tape to represent a comma in the Baudot code. During this tape punch cycle the tape feeding mechanism is operative in the regular way to feed the tape to the next column and the coded perforations are made on the tape to represent the digit 5 derived from the maintained sensing of the 4 card column of the record card C. This is performed during the following tape punch cycle by circuits now to be described.

Since the card carriage has not moved but remains at column 4 position, the floating cam contacts 149 are closed at the end of the tape punch cycle and when C1 cam contacts close the next tape punch cycle will be initiated by transmitting an impulse to clutch magnet 280. With the D4-8 contacts now restored to normal, tape punch magnets 290 will be selected during this next tape punch cycle in accordance

with the perforations appearing in the card column 4 of the record card C. During this tape punch cycle, cam contacts C2 will transmit an impulse to the escapement control magnet 40 to space the carriage from card column 4 to card column 5.

It will be recalled that in the previous tape punch cycle the E relay was energized when cam contacts C2 closed and was held energized by the closure of the FC contacts and since the E relay coil opened the E1 contacts the C relay coil is ineffective to control tape punching during the tape punch cycle now under consideration. Relay coil E deenergizes when the floating cam contacts 149 open at the end of this tape punch cycle. In this manner, punching under control of the C relay is now suppressed and the tape is perforated to represent the digit sensed on column 4 of the record card C and therewith 20 the card carriage will be spaced, and successive tape punching cycles will ensue to punch the tape to represent the digits of card columns 4, 5 and 6.

Upon completion of punching the tape to 25 represent the digit 8, the card carriages escape to card column position 7 at which time an extra tape punching operation will be effected in the manner just described, but a different code punching takes place on the tape.

30 At card column position 7 of the record card sensing unit, two successive tape punching operations are effected, the first of which causes the perforation of the tape at the 3 code position to represent a space. When this code position is 35 interpreted to control a tape controlled typewriter, a space will be effected between the units digit "8" of the printed number 128, 538 and "6", or the hundreds digit of the next printed number 621, as appears over the tape in Fig. 5. The following 40 tape punching operation causes the perforation of the tape to represent the digit 6. The extra tape punching operation to represent a space is effected by substantially the same circuit connections described for perforating the tape to represent the 45 comma designation, except that in this case, since the perforation is at the 9 index point position of card column 7 of the master card M, the A relay will be energized. The A relay closes the A1 relay contacts so that when C5 contacts close the 3 tape 50 punch magnet will be selected for operation. In the following tape punch cycle the statistical card C controls the punching of the tape to represent the "6" digit. Thereafter, punching of the tape to represent the digits 2 and 1 derived from the 55 card columns 8 and 9 of the record card C will be effected on the tape 200. At card column 10, the master card is perforated to initiate an extra tape punching operation to again perforate the tape to represent the space designation, this being 60 effected by again energizing the space control relay A.

In tape punching under control of the third card field, it will be noted that at column 12 of the master card, a perforation is sensed at the 8 index point position. This selects the B relay for energization and the latter closes its contacts B1, B2, B3 to select the 3, 4 and 5 tape punch magnets 290 to punch the corresponding code positions on the tape. From Fig. 4 it will be noted 65 that perforations at such code positions cause the printing of a period when the tape is interpreted to control a tape controlled printing machine.

At card column 14 of the master card, relay A is energized to again effect the perforation of the 70 tape to represent the space and at column 15 to

represent a comma by coded designations in the manner previously described. Upon sensing the last card column 18 of this card field the card carriage is skipped to the last card column position and thereafter the record card sensed is ejected from the machine, and a following record card is placed upon the card carriage and a repetition of the above described operations then takes place. The Doty patent gives a complete description of these incidental operations of the machine. However, the master card remains in the machine to cause the same functional operations for each of the following record cards. Whenever the requirement for interposition of the extra designations made upon the tape changes, a master card perforated at the required index point positions is placed in the master card sensing unit.

It is, of course, apparent that such extra designations made on the tape are not limited to those shown which are merely selected by way of example. Additional relays F, G, may be supplied beyond those designated A, B, and C and selected by other index point positions. The particular code positions which are perforated on the tape can be varied merely by the change in wiring between the contacts of the A, B, C and other relays F, G and the punch selecting magnets. Hence, the extra designations placed upon the tape can be varied at will.

While there have been shown and described and pointed out the fundamental novel features of the invention, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In a record controlled tape perforating system, the combination of a plurality of means for concurrently sensing a column of a record perforated to represent character representing data and a corresponding column of a supplemental record perforated to represent interpolated data, a tape perforator controlled successively by the respective sensing means to perforate the tape to represent said character representing data and said interpolated data, and sequencing means for effecting the operation of said tape perforator under control of said sensing means in succession.

2. In a tape perforating system, the combination of a plurality of means for concurrently sensing a column of a record perforated to represent character representing data and a corresponding column of a supplemental record perforated to represent interpolated data, spacing means to effect a relative movement of said sensing means and said records to the extent of a column, a tape perforator controlled successively by the respective sensing means to perforate the tape to represent said character representing data and said interpolated data, sequencing means for effecting the operation of said tape perforator under control of said sensing means in cyclic succession, and means for effecting the operation of said spacing means upon the second cyclic operation of said tape perforator.

3. In a tape perforating system, the combination of a record sensing means for concurrently sensing character representing perforated data in one column of one record and perforated data in a corresponding column of another record rep-

resenting interpolated data, a tape perforator, means to initiate and effect the operation of the tape perforator under control of the sensing means for perforating the character representing data, means under control of the interpolated data sensing means for suppressing the operation of the initiating means and for causing the operation of the tape perforator under control of said interpolated data sensing means to effect the perforation of the tape to represent said interpolated data, and means for thereafter effecting the operation of said tape perforator under control of the character representing data sensing means.

4. In a record perforating system, the combination of separate record sensing means for sensing two records concomitantly column by column, one of said records representing character representing data and the other interpolated data, a tape perforator for perforating a tape, and means operable at a predetermined column position of said records to effect successive cyclic operations of the tape perforator and including means to perforate said tape under control of said sensing means to represent the character representing data and the interpolated data.

5. In a perforating system, the combination of record sensing means for sensing two records concomitantly column by column, one of said records representing character representing data and the other interpolated data, a tape perforator for perforating a tape, and means operable at a predetermined column position of said records to effect successive cyclic operations of the tape perforator and including means to first perforate said tape under control of the interpolated data sensing means to represent the interpolated data and then under control of the character representing data sensing means to represent the character representing data.

6. In a perforating system, the combination of separate record sensing means for sensing two records concomitantly column by column, one of said records representing in statistical code character representing data and the other representing by differentially located perforations other interpolated data, a tape perforator for perforating a tape, and means operable at a predetermined column position of said records to effect successive cyclic operations of the tape perforator and including means to perforate said tape under control of said sensing means to represent in combinational code both the character representing data and the interpolated data.

7. In a record controlled tape punching apparatus, the combination of record sensing means for sensing statistical code designations on said record, a tape perforator controlled by said record sensing means including translating means for perforating a tape in a combinational code, means for concurrently sensing other designations on a record material representing designations to be interpolated on said tape, a plurality of relays selectively energized under control of said last named sensing means, and means under control of each of said relays to select punches of said tape perforator to perforate the tape to represent the interpolated designation in said combinational code.

8. In a record controlled telegraphic tape punching apparatus, the combination of record sensing means for sensing statistical code designations of said record, a tape perforator controlled by said record sensing means and including translating means for perforating a tape in a

combinational code, means for concurrently sensing other designations on a record material representing designations to be interpolated on said tape, a plurality of relays selectively energized under control of said last named sensing means, and means to effect the operation of said tape perforator under control of the selected relay to effect extra coded perforations on the tape to represent the interpolated designations.

9. In a record controlled telegraphic tape punching apparatus, the combination of record sensing means for sensing statistical code designations of said record, a tape perforator controlled by said record sensing means and including translating means controlled by said record sensing means for perforating a tape in a combinational code, means for concurrently sensing other perforations on a record material in statistical code representing designations to be interpolated on said tape, and means operable at predetermined column positions of said record to effect the operation of said tape perforator under control of said last named sensing means to effect extra perforations on the tape in said combinational code to represent the interpolated designations.

10. In a system for perforating a tape under control of a statistical record, a tape perforator, record sensing means for sensing said statistical record for controlling said tape perforator, source means comprising a supplemental perforated record for storing coded designations to be interpolated on said tape, sensing means for sensing said supplemental record, and means for suppressing the operation of the tape perforator under control of said first named sensing means when said second named sensing means encounters perforations on the supplemental record and to effect the operation of the tape perforator under control of said supplemental record sensing means.

11. In a system for perforating a tape under control of a statistical record, a tape perforator, record sensing means for sensing said statistical record for controlling said tape perforator, source means comprising a supplemental perforated record for storing at successive column positions and at differentially located positions coded designations to be interpolated on said tape, sensing means for sensing said supplemental record, and means for suppressing the operation of the tape perforator under control of said first named sensing means when said second named sensing means encounters perforations on the supplemental record and including means to effect the operation of the tape perforator under control of said supplemental record sensing means to record coded designations on said tape according to the differential locations of the perforations on the supplemental perforated record.

12. In a tape perforating system, the combination of storage means for storing up code designations to be interpolated on a tape, a tape perforator, means for sensing a record for controlling said tape perforator, and means operable at predetermined column positions of said record to effect the additional operation of the tape perforator under control of said storage means to interpolate predetermined designations on said tape.

13. In a tape perforating system, the combination of a plurality of storage means, each for storing up code designations to be interpolated on a tape, a tape perforator, means for sensing a record for controlling said tape perforator, and means operable at predetermined column posi-

tions of said record to select a storage means and to effect the additional operation of the tape perforator under control of the selected storage means to interpolate the code designations stored therein on said tape.

14. In a tape perforating system, the combination of a plurality of storage means, each for storing up code designations to be interpolated on a tape, a tape perforator, means for sensing a record for controlling said tape perforator, record controlled means for selecting a storage means, and means operable at predetermined column positions of said record to effect the additional operation of the tape perforator under control of the selected storage means to interpolate the code designations represented thereby on said tape.

15. In a system for perforating a tape, the combination of a tape perforator, a plurality of transmitters comprising a record controlled transmitter for transmitting intelligence represented by a perforated record to control said tape perforator, and a supplemental record controlled transmitter including code designation storage means for controlling said tape perforator for transmitting interpolated coded designations on said tape, and means controlled by said supplemental record controlled transmitter for suspending the operation of the first named transmitter and to initiate the operation of the supplemental record controlled transmitter for controlling said tape perforator to perforate the tape under control of a selected designation storage means.

16. In a system for perforating a tape, the combination of a tape perforator, a plurality of transmitters comprising a record controlled transmitter for transmitting intelligence represented by a perforated record to control said tape perforator, and a supplemental record controlled transmitter including a plurality of code designation storage means for controlling said tape perforator for transmitting interpolated coded designations on said tape, and means controlled by said supplemental record controlled transmitter for selecting a code designation storage means and for suspending the operation of the first named transmitter and to initiate the operation of the supplemental record controlled transmitter for controlling said tape perforator to perforate the tape under control of said selected designation storage means.

17. In a tape perforating system, the combination of a tape perforator, record controlled sensing means including a plurality of selectively operated data storage means for controlling said tape perforator, a supplemental record controlled sensing means for controlling said tape perforator, means controlled by said first named record controlled sensing means for selecting a storage means and for suspending the operation of the tape perforator under control of the supplemental record controlled sensing means and for causing the operation of the perforator to perforate code combinations determined by the selected data storage means, and means operable following the operation of the tape perforator under control of a selected storage means to resume the operation of the tape perforator under control of the supplemental record controlled sensing means.

18. In a tape perforating system, the combination of a tape perforator, record controlled sensing means including a plurality of data storage means selected thereby for controlling said tape perforator, a supplemental record controlled sensing means for controlling said tape perfor-

rator, means controlled by said first named record controlled sensing means for disconnecting the latter from said tape perforator for suspending the operation of the tape perforator under control of the supplemental record controlled sensing means and for connecting a selected storage means to said perforator for the operation of the perforator to perforate code combinations determined by the selected data storage means, and means operable following the tape perforation operation under control of a selected storage means for connecting said supplemental record controlled sensing means with said tape perforator to resume operation thereof under control of said supplemental record controlled sensing means.

19. In a record controlled tape perforating apparatus, the combination of a record sensing means for sensing a record perforated according to a statistical code column by column, a tape perforator controlled thereby for perforating a tape according to a combinational code, means comprising a supplemental perforated record sensed column by column concomitantly with the first named record for storing up according to the statistical code designations to be interpolated on said tape in the combinational code, and means to effect at a plurality of predetermined sensed columns the operation of said tape perforator under control of said supplemental record to perforate the tape to represent the interpolated designations according to the combinational code, and means operable following each cyclic operation of the tape perforator for the interpolated designations for effecting the cyclic operation of the tape perforator under control of the first named sensing means to perforate the tape to represent the data in the column concurrently

sensed with the corresponding column of the supplemental record bearing the designation to be interpolated.

20. In a record controlled tape perforating system, the combination of a plurality of means for sensing a column of a record perforated to represent character representing data, and a companion column of a supplemental record perforated to represent interpolated data, a tape perforator controlled successively by the respective sensing means to perforate the tape to represent said character representing data and said interpolated data, and sequencing means for effecting the operation of said tape perforator under control of said plurality of sensing means in succession.
21. In a record controlled tape perforating system, the combination of a tape perforator and record controlled means to control the operation of said tape perforator to perforate a tape to represent data on said record, means to sense "space" code holes and/or "punctuation" code holes on a supplemental record, and means controlled by said sensing means to control said tape perforator to perforate desired positions of said tape to represent such punctuation and/or space designations.

22. In a record controlled tape perforating system, the combination of a tape perforator, record controlled means to control the operation of said tape perforator to perforate a tape to represent data on said record, and means supplemental to said record controlled means to intermittently control said tape perforator to perforate desired positions of said tape to represent punctuation and/or space designations demarcating said data.

CHARLES R. DOTY.
